UNITED STATES PATENT OFFICE

FRED J. BURNS, OF SAGINAW, MICHIGAN, ASSIGNOR TO THE COLUMBIA MILLS, INC.,
OF SAGINAW, MICHIGAN, A CORPORATION OF NEW YORK

VENETIAN BLIND

Application filed September 26, 1930. Serial No. 484,565.

This invention relates to venetian blinds provided with a case in which the blind operating mechanism is mounted, and is more particularly directed to the mounting of the transverse roller therein, and on which the support and operating cords are wound.

One object of the invention is to provide a neat and substantial case in which said roller is mounted, and provide plates on the ends of said roller mechanism for removably engaging the ends of said case.

Another object is to provide detachable supports or bearings for use with blinds of extreme width, so that the transverse operating roller may be held in proper alignment, and prevent binding, misalignment, and consequently faulty operation of the mechanism.

A further object is to provide a mechanism so constructed that the entire blind structure can be demounted from the window frame as a unit, so that windows can be readily cleaned, repaired, or as occasion or necessity may require.

The above and other objects will appear as the specification progresses, reference being had to the accompanying drawings, in which I have shown the preferred embodiment of my invention, and in which like reference numerals indicate like parts throughout the several views thereof.

In the drawings:

Fig. 1 is a front view of a venetian blind made in accordance with my invention.

Fig. 2 is an enlarged front view showing the case with the cover removed, and the transverse operating roller mounted therein.

Fig. 3 is a top plan view illustrating the removal of the roller from the case.

Fig. 4 is a front view of one of the end plates.

Fig. 5 is an end view thereof.

Fig. 6 is a view similar to Fig. 4 showing the opposite end plate.

Fig. 7 is an end view.

Fig. 8 is an end view of the case showing the detachable plate covering the opening, the dotted lines illustrating its removal.

Fig. 9 is a similar view showing the top of the case open.

Fig. 10 is an enlarged front view illustrating one of the intermediate bearings and its mounting.

Fig. 11 is a part sectional end view.

Referring now more specifically to the drawings, the numeral 5 indicates a window frame or casing to which a pair of brackets 6 are secured by means of screws or the like, a preferably sheet metal case 7 being demountably supported on these brackets, and a transversely disposed roller 8 is removably mounted therein.

The roller 8 is preferably formed of pipe and is provided with spaced apart enlarged sections 9 and 10 respectively, blind support cords 11 and 12 being anchored thereto so that the cords may be wound thereon, the opposite ends of said cords being secured to the end slat 13 of the blind. A larger section 14 is provided directly adjacent the section 9, and an operating cord 15 is adapted to be wound thereon, and it will be obvious that as the cord is wound on or unwound from the roller, that the slats will be raised or lowered accordingly, these enlarged sections can be formed of wood or any other desired material, and are anchored in position on the pipe in any approved manner, or the roller may be a solid shaft, or may be formed in one piece having these enlarged sections formed integral therewith.

In the construction shown in Figs. 2, 3 and 8 of the drawings, the front of the case is shown open, and a detachable snap cover plate 16 forms a closure for said opening, a slightly different construction being shown in Fig. 9, and in which the top of the case is open, no cover plate being required due to the fact that the top is concealed from view when the case is in position on the window frame, however, a cover can be provided should it be desired.

The ends of the case are formed of individual plates 17 securely welded or riveted to the top, bottom and back wall, the top and bottom edges of said end plates being bent inwardly and thence upwardly and inwardly as shown at 18, to form ways in which end plates 19 and 20 respectively are slidably mounted, the end plate 19 being formed with

a laterally projecting stub shaft 21, which is adapted to be inserted in one end of the pipe member 8, and in which said pipe is journaled, the opposite plate 20 being formed in an identically similar manner, excepting 5 that the laterally projecting member 22 is threaded and engages the opposite end of the roller 8, this end being interiorly threaded to engage said threaded member so that when the roller is actuated by operation of the operating cord, the roller will be shifted transversely, and the support cords and operating cord will be evenly wound thereon and raise the slats, rotation of the roller in the reverse direction shifts the transverse roller in the opposite direction, and the slats are lowered by gravity.

In rollers of extreme length one or more intermediate supports and bearings are provided, one support and a bearing being shown 20 in Figs. 10 and 11, this comprises a vertically disposed plate member 23, the edges of which are turned and secured to the case by welding or rivets, (not shown), the front edge of the plate being shaped as shown at 24 to accommodate the bearing member 25 in which the pipe member 8 is journaled, the top and bottom edges of said bearing being grooved to slidably engage the edges of the plate, so that when it is desired to remove the roller, the bearing readily slides out of position.

Suitable openings are provided in the bottom wall of the case to accommodate the support and control cords, and conventional 35 grummets 26 are inserted to provide a rounded edge to prevent excessive wear of the cords. Where the window openings are of limited width it will of course be obvious that no intermediate supports and bearings 40 are required, and it will also be understood that the ends of the case may be formed in various other ways to permit the end plates to be slidably inserted or removed without departing from the spirit of the invention.

45 The device is easy and simple to remove, is very economical to manufacture, and is of neat and pleasing appearance, the case being painted to harmonize with the woodwork or color scheme in the home or building.

50 From the foregoing description it will be obvious that I have perfected a very simple, practical, and convenient venetian blind mounting.

What I claim is:—

55 1. In a venetian blind having a plurality of spaced apart slats, the combination with a supporting member, end plates removably mounted on said supporting member, and a winding roller mounted on said end plates 60 and shiftable endwise as the roller is wound, said plates being removable as a unit with said roller.

2. A venetian blind including a case, end plates removably mounted in said case, and 65 a transversely shiftable operating roller re-

movably journaled on said end plates and shiftable endwise as the roller is wound, said roller being removable as a unit with said plates.

3. A venetian blind mechanism including 70 a case, a pair of end plates removably mounted therein and formed with laterally projecting stub shafts, and a transversely disposed winding roller mounted on said stub shafts and removable as a unit with said end plates. 75

4. A venetian blind mechanism including 80 a supporting member, end plates removably mounted thereon and formed with centrally disposed laterally projecting stub shafts, a transversely shiftable winding roller journaled thereon, said roller being removable as a unit from said supporting member. 85

5. A venetian blind mechanism including 90 a case, end plates mounted to slide therein and formed with inwardly projecting stub shafts, a transversely shiftable roller journaled on said stub shafts, and having spaced apart enlarged winding sections, said end plates and roller being removable as a unit from said case. 95

6. A venetian blind mechanism including 100 an open case, stub shafts removably mounted in said case and projecting inwardly from the ends thereof, a transversely shiftable winding roller journaled on said stub shafts and removable as a unit with said winding roller, and a detachable cover plate forming a closure for the opening in said case. 105

7. A venetian blind including a case, end plates removably mounted therein, a transversely shiftable winding roller journaled thereon and provided with an intermediate bearing, an intermediate support in which 110 said bearing is removably mounted, said end plates, winding roller, and bearing being removable as a unit from said case.

8. A venetian blind including a case provided with an intermediate support, end plates removably mounted in said case, a transversely shiftable winding roller journaled on said end plates and provided with a bearing intermediate its length adapted to be mounted in said support, said end plates, 115 roller, and bearing being assembled in or removable from said case as a unit.

9. A venetian blind including a supporting member having an intermediate support, end plates removably mounted on said support, a transversely shiftable winding roller journaled thereon and provided with a bearing intermediate its length, and mounted in 120 said support, said end plates, bearing, and roller being removable as a unit from said supporting member.

10. A venetian blind including a case provided with an intermediate bearing support, end plates removably mounted in said case, a transversely shiftable winding roller, a bearing mounted thereon and detachably engaging said bearing support, said end plates, 125 130

roller, and bearing being removable as a unit from said case.

11. A venetian blind including a supporting member, a winding roller adapted to be shifted endwise as the roller is wound, stud shafts on which said roller is mounted, said stud shafts being removable as a unit with said winding roller.

5 In testimony whereof I hereunto affix my
10 signature.

FRED J. BURNS.
